UNITED STATES PATENT OFFICE

PETER O. BORGESON, OF MIAMI, FLORIDA

WINDOW HINGE

Application filed May 9, 1930. Serial No. 451,094.

This invention relates to window hinges and has for an object to provide a hinge adapted to so mount a casement window on the casing thereof, that the window may be 5 reversed when open in order that the outside of the window pane may be washed from the inside of the room.

A further object is to provide an extremely simple, strong and durable casement window 10 hinge which will be formed of a few parts that will be inexpensive to manufacture and will not easily get out of order.

A still further object is to provide a window hinge in which both of the hinge 15 leaves may be locked closed to lie flat against the window frame and will permit of the window being opened or closed in the usual manner, said locking means being adapted to be easily and conveniently released to 20 permit of said leaves being rocked open whereby the window may be reversed for washing the window pane.

A still further object is to provide a hinge one of the leaves of which is equipped with 25 an angle iron support which may be secured to the edge and front face of the window frame and will reinforce the frame while at the same time will house the locking means and protect same from exposure to the 30 weather,

With the above and other objects in view the invention consists in certain novel details of construction and combinations of parts hereinafter fully described and claimed, 35 it being understood that various modifications may be resorted to within the scope of the appended claims without departing from the spirit or sacrificing any of the advantages of the invention.

10 In the accompanying drawings forming part of this specification,

Figure 1 is a cross-sectional view of a casement window equipped with my improved hinge and also showing the operating mechanism for opening and closing the window,

Figure 2 is a cross-sectional view similar to Figure 1, but showing the window open and reversed to permit of the outside of the window pane being washed from inside the 50 room,

Figure 3 is a fragmentary front elevation showing my improved hinge applied to a casement window and the window casing thereof,

Figure 4 is an end elevation showing the hinge applied to a casement window and the window casing thereof and showing the grip of the locking latch housed within a depression in the housing,

Figure 5 is a detail sectional view taken on the line 5—5 of Figure 4, showing the locking latch in operative position and also dotted in released position, and

Figure 6 is a front elevation of the inner leaf.

Referring now to the drawings in which like characters of reference designate similar parts in the various views, 10 designates a window casing, 11 the frame of a casement window, the window having the usual glass pane 12, and 13 designates in general a window screen which as usual in casement window construction is mounted in the window casing inside the window.

In carrying out the preferred embodiment 75 of the invention I provide a hinge comprising leaves 14 and 15, said leaves being provided with eyes 16 through which a pintle 17 is passed to hingedly connect the leaves. The leaves normally lie flat against each other as 80 best shown in Figure 1, to permit of the window being opened in the usual manner to the position shown in dotted lines in Figure 1. However, the leaves are adapted to open as best shown in Figure 2 when it is desired to 85 reverse the window for washing the outside of the window pane as will be hereinafter described in detail.

The outer leaf 14 is provided with an offset leg 18 remote from the pintle, said offset leg extending substantially at a right angle to the leaf 14 as best shown in Figure 2. A flange 19 as best shown in Figures 1 and 2 projects laterally from the leg 18 and rear end of the leaf 14 and is terminally equipped with eyes 20 as best shown in Figure 3; through which and similar eyes 21 carried by an attaching plate 22, a pintle 23 is passed. The attaching plate is preferably 100

secured by screws 24 to the window casing 10.

A locking lug 25 is secured to the offset leg 18 and projects beyond the inner face of the leg. A kerf 26 is formed in the lug to receive the locking latch hereinafter described for holding the leaves 14 and 15 closed, that is lying flat one against the other.

By now referring to Figures 4, 5 and 6, it will be seen that the inner leaf 15 is provided with an offset leg 28 similar to the offset leg 18 of the outer leaf 14, and said leg as well as the rear end of said inner leaf 15 is provided with a flange 28. The numeral 29 designates in general a plurality of screws 15 which secure the inner leaf 15 as well as the flange 28 thereof to the window frame 11. The above mentioned locking lug 25 passes through an opening 30 formed in the offset leg 27 of the inner leaf 15 and is receivable in a recess 31 formed in the window frame.

A locking latch 32 is pivoted as shown at 33 in Figure 5 to the leg 27 of the leaf 15. The latch extends through a slot 34 formed in the flange 28 and is terminally bent laterally to provide a grip 35. The flange 28 is depressed as shown at 36 to receive the grip so that the latter will extend flush with the face of the flange when the latch is in locked position, and above the depressed portion the flange 28 is provided with a second depression or thumb recess 37 into which the grip 35 projects so as to be readily opened by the thumb of the operator. The locking latch is receivable in the kerf 26 of the above described locking leg to lock the inner and outer leaves together as will be obvious.

The operating mechanism for opening and closing the window is of the type described in my co-pending application filed of even date herewith, and comprises in general a handle lever 38 which is turnable on a pivot 39 to operate a lever arm 40. The lever arm is terminally slotted as shown at 41 to receive a pivot pin 42 of a connecting link 43. The connecting link is terminally equipped with an eye 44 which is pivoted on the link as shown at 45 and encircles a guide rod 46 that is terminally secured to the window frame. When the pivot pin 42 of the link 43 is disposed at the inner end of the slot 41 the link extends in alignment with the lever arm 40 as best shown in Figure 1 and is detachably secured in this position by means of a pivoted catch 47 which is terminally equipped with a lip 48 which engages in a notch 49 formed in the link 43.

The operating lever 38 which normally extends along the window sill may be first moved to extend at an angle to the window sill as shown in Figure 1 and then may be rocked to rock the lever 40 and link 43 to the position shown in dotted lines in Figure 1 to open the casement window in the usual manner. Should it be desired to reverse the win-

dow to the position shown in Figure 2, it will be necessary to disengage the catch 47 and move the link 43 outwardly so that the pivot pin 42 thereof is disposed at the outer end of the slot 41 whereupon the operating lever 38, as shown in Figure 2, may be rocked in the reverse direction from that used to open the window whereupon the inner and outer leaves 14 and 15 of the hinges will be opened and will reverse the casement window so that the outside of the window pane faces inwardly and may be washed from the interior of the room. It is of course understood that the above described locking latches 32 of both the upper and lower hinges will be released to permit of the leaves of the hinges being opened as just described.

It will be observed that the offset leg 27 and flange 28 of the inner leaf form a housing for the lock latch and protect the same from the weather as well as reinforce the window frame at the edges of the recess 31.

It will be still further observed that the hinge constructed as above described will be strong and durable and will consist of but a few parts which will not easily get out of order.

It will be pointed out that my improved device as above described is equally applicable to steel casement windows as well as wood casement windows and that such modifications as are necessary to apply the device to steel in lieu of wood fall within the scope of this invention.

Having thus described the invention, I claim:

1. A window hinge comprising inner and outer leaves pivotally connected together, said inner leaf being adapted to be secured to a window frame, said outer leaf being adapted to be secured to a window casing, both of said leaves having offset legs projecting substantially at a right angle to the respective leaves, a locking lug carried by one of said legs, and a locking catch for engagement with said lug carried by the other of said legs.

2. A window hinge comprising a pair of leaves one of which is adapted to be secured to a window casing and the other of which is adapted to be secured to a window frame, a locking lug projecting from one of said leaves and extending through an opening in the other of said leaves, and a pivoted catch carried by the last named leaf and adapted to engage in a kerf formed in said locking lug and hold said leaves folded together in flat position.

3. A window hinge comprising a pair of leaves pivotally connected together at the outer ends thereof, one of said leaves being provided with a laterally disposed flange, a securing plate adapted to be rigidly secured to a window casing and pivotally secured at the free end of said flange, the other of said leaves being adapted to be rigidly secured

to a window frame and having a laterally disposed flange, a locking lug projecting from the inner face of one of said leaves and receivable in an opening formed in the other 5 of said leaves, and a locking latch carried by the flange of the last named leaf adapted to engage said locking lug.

In testimony whereof I affix my signature.

PETER O. BORGESON. [L.S.]
